INVENTOR:
RICHARD J. MOORE.
BY W. L. Dempsey,
ATTORNEY.

UNITED STATES PATENT OFFICE

RICHARD J. MOORE, OF EAST ST. LOUIS, ILLINOIS

TEMPLATE

Application filed April 2, 1930. Serial No. 441,026.

This invention relates to templates and more particularly to a template for use in road construction for the purpose of giving a proper contour to the concrete surface of a highway.

The chief object of this invention is to provide an efficient and economical device for smoothing down and giving the proper contour to the surface of a concrete road.

10 Other objects and advantages of this invention will be disclosed in the specification, claims and drawings, in which:

Fig. 1 is a front elevation of the template superimposed on a cross-section of a concrete road.

Fig. 2 is a plan view of the device.

Fig. 3 is a cross-section of Fig. 2 along the line 3—3 in Fig. 2.

20 Fig. 4 is a cross-section of a portion of a concrete road showing in enlarged detail one side of the device.

Fig. 5 is a similar view to Fig. 4, showing the device in a different position.

25 In building concrete roads it is the custom to provide a crown in the center of the road varying in elevation according to the width of the road. It is, also, customary to face the edges of the road with suitable metal facing, usually some form of angle steel.

30 In order that the road present a smooth, flat surface of proper curvature, it is necessary to plane down or strike off the concrete to give it proper contour, while the concrete is still in a plastic condition. Heretofore this function has been performed by hand, and in order to expedite this work and provide an absolutely uniform contour to the surface of the road, I have devised the present invention.

40 The preferred method of construction of my device provides for a transverse beam 1 preferably fabricated from two angle bars 2, between which are bolted flat iron or steel bars 3. The bars 3 are supported by the angle bars 2 in such a manner that they will lie at an angle to the straight angle bars 2, the degree of angularity depending upon the amount of crown given to road. This is indicated by the dotted lines 4 in Fig. 1.

The transverse beam 1 when in use is supported at each end by the angle steel facings 5 which face the edges of the road. Near each end of the transverse beam 1, identical levers 6 having curved lower ends 7, are pivotally joined at 8 to the transverse bar 1 and pivotally connected at 9 to the transverse rod 10, which may be provided with a turn buckle 11 to permit suitable adjustments.

When the concrete 12 has been poured and filled in the proper depth between the facings 5, and while it is still in a plastic condition, the transverse beam 1, being supported on top of the facing, as best shown in Fig. 1, is drawn longitudinally forward by means of suitable cables 13 which may be attached to a tractor or other suitable motive power.

55 The transverse movement of the template is manually regulated and controlled within narrow limits, usually from two to three inches, by the levers 6 operated by one man walking on either side of the road. The lower outside portion of the levers 6 contact with the inner upper facing 5 so that the movement of either one of the levers shift 75 the cross beam longitudinally, one or the other of the levers being always in contact with one side of the facing.

60 It is obvious that the crown of the road may always be centrally located in spite of 80 the longitudinal curvature of the road or the direction of pull on the cables 13.

65 It is, therefore, evident that not only will the crown of the road be properly centered, but the entire surface of the road will be 85 uniform throughout its length.

70 While the members 3, as shown in Fig. 1 of the drawings, are bolted to the side members 2 of the transverse beam, I wish it understood that the vertical position of these members can be raised or lowered by simply drilling additional holes through the members 3 so that the surface of the concrete may be struck off at any desired depth. As shown in Fig. 1, the surface of the road is being struck off 95 approximately 2 inches below the upper surface when completed for the purpose of providing a smooth surface for the wire netting reinforcement.

75 Having fully described my invention, what 100

I claim as new and useful and desire to protect by Letters Patent is:

1. An improvement in templates of the class described comprising, a cross beam fabricated of two angle irons joined together, a flat bar affixed between said angle irons so that the longitudinal axes of said bar and said angle irons lie at an angle to each other, vertically disposed levers pivotally joined through the ends of said beam, the lower ends of said levers being curved to adopt them to contact with the inner surfaces of the metal facing of a concrete road, a tie rod having one of its ends pivotally attached to the other said lever whereby a parallelism is maintained between said levers when either one is rotated about its pivotal point, said tie rod consisting of two members joined together by a turn buckle for maintaining said levers in parallel relations to each other.
2. An improvement in templates for surfacing concrete roadways, of the class described, comprising a beam fabricated from a plurality of metal angles and plates longitudinally joined together so that the longitudinal axes of the angles will lie at an angle to the longitudinal axes of the plates, the said angles being longer than the said plates and so joined thereto that the said angles will project beyond the said plates at both ends, said projecting ends of said angles having smooth flat under-surfaces adapting them to slidably move along the upper-surfaces of movable metal side forms, said metal plates depending from said angles and being of slightly less length than the width of the roadway between said side forms to permit a limited lateral movement of said fabricated beam when moved longitudinally of said roadway.

In witness whereof I have hereunto affixed my signature this 15th day of March, 1930.

RICHARD J. MOORE.
